FLY-SWATTER.

1,237,081.

Specification of Letters Patent. Patented Aug. 14, 1917.

Application filed February 27, 1917. Serial No. 151,274.

To all whom it may concern:

Be it known that I, JAMES L. MOTT, Jr., a citizen of the United States, residing at Franklin Square, L. I., of the town of 5 Hempstead, in the county of Nassau and State of New York, have invented new and useful Improvements in Fly-Swatters, of which the following is a specification.

The invention has reference in general to insect destroyers, and more particularly to devices of this character known as fly swatters.

The primary object of the invention resides in the production of a device of this character wherein the wire cloth or the like 15 commonly used in the construction of fly swatters is detachably connected to the handle in a novel and convenient manner in order that the same may be readily removed and replaced as the occasion may so demand.

20 The invention, among other features, comprehends the provision of a handle which is so formed to provide contiguous therewith, a clamp for holding the cloth or striking element of the swatter to the handle.

25 With the above and other objects in view, the invention consists in the novel features, details of construction and combination of parts which will hereinafter be more fully set forth, illustrated in the accompanying 30 drawing and pointed out in the appended claims.

Figure 1 is a face view of the swatter;

Fig. 2 is a perspective view of the handle with the striking element of the swatter re- 35 moved therefrom; and

Fig. 3 is a top plan view.

Referring more particularly to the accompanying drawing, in which like characters of reference refer to corresponding 40 parts in the several views, A denotes a wire cloth or the like commonly used in the construction of fly swatters and for the sake of clearness the same will be hereinafter referred to as the striking element, shown as 45 connected with a handle denoted generally by the character 5.

This handle 5 is constructed from a single strand of wire 6 bent at its medial portion to provide a looped hand grip 7, and 50 thence intertwined forming a shank 8. At the outer or free end of the shank 8 the intertwined strands of the wire are separated and bent to provide a pair of diverging offset branches 9, and the manner of positioning these diverging branch portions with re-

spect to one another forms at the forward or upper extreme end of the shank a substantially V-shaped space 10. Each of the branch portions 9 is terminally bent in an outward horizontal direction to provide a 60 clamp 11. This clamp 11 consists of a pair of substantially L-shaped jaws 12 arranged in an offset horizontal plane with respect to one another, and each embodying a rigid horizontally disposed arm 13 and a yieldable arm 14 connected with one another by the vertically arranged bight 15. The length of the yieldable arm 14 exceeds the length of the rigid arm 13, thus positioning the protruding extremity 16 of each of the 70 yieldable arms 14 within the V-shaped space 10 for a purpose to be hereinafter more fully set forth. The free extremity of each of the protruding portions 16 terminates in eyes 17 through which the threaded bolt 18 projects and on which the nut 19 is threadedly mounted.

In the operation of the device, the bottom transverse edge of the striking element A is inserted between the rigid arm and the 80 yieldable arm of each of the jaws and downwardly in the vertical bight portions 15, after which the eyes 17 of the protruding portions 16 of the yieldable arms are brought into alinement or registration with one another by compressing the diverging branch portions 9. After the eyes are properly aligned with one another the bolt 18 is inserted in one of the eyes and through the striking element A and extended in the other 85 90 of said eyes and on which the nut 19 is threaded. It will, therefore, be apparent to those skilled in the art to which the invention relates that the vertical bight portions 15 grip the striking element at points adjacent its free longitudinal edges, thus establishing a firm connection, through the co-operation of the rigid and resilient clamping arms of the striking element to the 95 handle.

From the foregoing description, taken in connection with the accompanying drawing, the advantages of construction and the method of operation will be readily apparent to those skilled in the art to which the 105 invention relates, and while I have described the principles of operation of the invention, together with the device which I now consider to be the best embodiment thereof, I desire to have it understood that the device 110

shown is merely illustrative and that such changes may be made when desired as are within the scope of the appended claims.

What is claimed as new, is:—

- 5 1. A fly swatter embodying a handle having a shank, a pair of diverging branch portions on the upper end of said shank, a clamp formed contiguous with said branch portions and terminally provided with eyes, 10 a wire fabric adapted to be inserted in the clamp, the eyes of the clamp registering with one another upon the compression of said diverging portions, and a fastening device projecting through said eyes and said 15 wire fabric.
- 20 2. A fly swatter embodying a handle constructed from a single length of wire looped at its medial portion to form a hand grip, the wire being thence intertwined to provide a shank, a pair of diverging branch portions formed at the free end of the shank, a jaw formed integral with each branch portion, a wire fabric adapted to be inserted in said jaws, said jaws being movable in a direction toward one another upon the compression of said diverging portions, and a fastening device projected terminally through said jaws and said wire fabric. 25

3. A fly swatter including a shank formed at its upper end with a V-space, a pair of 30 horizontally arranged clamping jaws formed contiguous with said shank, each jaw consisting of a rigid arm and a resilient arm, a wire fabric adapted to be inserted between the arms of said jaws, the said resilient arm being of greater length than the rigid arm, the protruding extremity of the resilient arm projecting in the V-shaped space of said shank, and a fastening device 35 projecting through the terminals of the resilient jaw and through the said wire fabric. 40

4. A fly swatter embodying a handle formed from a single strand of material, a pair of horizontally arranged L-shaped 45 clamping jaws formed contiguous with said handle, a wire fabric adapted to be inserted in the jaws of said handle, and a fastening device projecting through the free terminal of each of said jaws for securing the wire fabric therein. 50

In testimony whereof I affix my signature in presence of two witnesses.

JAMES L. MOTT, JR.
